UNITED STATES PATENT OFFICE.

VICTOR W. THAYER, OF SYRACUSE, NEW YORK, ASSIGNOR OF ONE-HALF TO
WALTER H. NYE, OF SYRACUSE, NEW YORK.

TOOL.

1,358,037.

Specification of Letters Patent.

Patented Nov. 9, 1920.

Application filed May 12, 1920. Serial No. 380,900.

To all whom it may concern:

Be it known that I, VICTOR W. THAYER, of Syracuse, in the county of Onondaga, in the State of New York, have invented new and 5 useful Improvements in Tools, of which the following, taken in connection with the accompanying drawings, is a full, clear, and exact description.

This invention relates to certain improvements in tools adapted to operate upon the work with a rotary motion, and involves the use of a universal joint as a part of the tool whereby the part which holds the work or another tool and the part to which the power 10 is applied for turning may be caused to rotate about axes at different angles to each other or about one and the same axis.

The invention is particularly adapted for use as a socket wrench for receiving and supporting various forms and sizes of sockets as 15 may be required for operation upon bolts and nuts of different forms and sizes, although it is evident that the same tool may be used for rotating other tools.

20 The main object is to utilize any one of the several forms or sizes of sockets as one of the members of the universal joint in such manner that it may be easily and quickly detached or replaced to and from its companion member in such manner that both 25 may be free to turn about axes which are disposed in planes at right angles to each other and some distance apart across the axis of the handle.

30 Another object is to provide yielding means for holding the socket against accidental displacement from its companion member, and, at the same time, to permit the socket member to be easily removed against 35 the resistance of the yielding member when turned to its certain angle relatively to the companion member.

40 Other objects and uses relating to specific parts will be brought out in the following 45 description.

In the drawings:

Figure 1— is a side elevation of a socket wrench embodying the various features of my invention, the central portion of the handle being broken away, the dotted lines indicating different positions of adjustment of the socket and its companion member.

Fig. 2— is a side elevation of the same

wrench taken at right angles to that shown in Fig. 1—, in which the dotted lines indicate different positions of adjustment of the socket member of the universal joint.

Figs. 3— and 4— are longitudinal sectional views taken, respectively, on lines 3—3, Fig. 1, and 4—4, Fig. 2—.

Figs. 5—, 6— and 7— are perspective views, respectively, of the universal joint members consisting of the head of the handle, the coupling block and socket member.

As illustrated, this tool comprises a cylindrical rod or shank 1— of any suitable length having end heads 2— and 3— rigidly secured thereto, one of said heads being provided with a transverse or diametrically extending opening 4— in which is fitted a cross-bar 5—, which, together with the shank 1—, constitutes what may be termed the handle.

The head 3— is secured to one end of the shank 1— by means of a key or pin 6— and has its opposite end provided with a pair of axially extending lugs or ears 7— in transversely spaced relation, said ears being provided with apertures for receiving a pivotal pin 8— which extends across the intervening space, as 9— between the ears.

A coupling block 10— is mounted at one end upon the pivotal pin 8— to swing about the axis of said pin within the space 9— between the ears 7—, the outer end of said block being provided with a central lengthwise slot 11— extending inwardly from its outer end a distance somewhat less than the distance between said outer end and the axis of the pivotal pin 8—, said slot being disposed in a plane at right angles to that of the pivotal pin 8— and terminates at its inner end in a cylindrical bearing 12— of slightly greater diameter than the transverse width of the slot 11— for receiving one end of a socket member 13—.

The outer end of the socket member has a substantially circular exterior and an angular interior, the cross-sectional form of the latter corresponding to the form of the nut or bolt over which it is adapted to fit. The socket 13— is provided with opposite inwardly projecting ears or lugs 14— spaced apart a sufficient distance to receive between

them the outer end of the coupling block —10—, and are provided with apertures for receiving a pivotal pin —15—, which is movable in the slot —11— into and out of registration with the circular bearing —12—. The opposite ends of the pivotal pin —15— are rigidly secured in the ears —14— to turn with the socket —13—, the diameter of said pin between the ears —14— at right angles to the axis of the socket being substantially equal to that of the circular bearing —12—, and, therefore, of greater width than that of the slot —11—, the remaining opposite sides of said pivotal pin being preferably flattened or of a width substantially equal to or slightly less than that of the slot —11—.

It, therefore follows that in order to insert the pivotal pin —15— through the slot —11— and into the bearing —12—, the socket must be turned so that its axis will be at substantially right angles to that of the coupling block —10—, or to the position indicated by dotted lines in Fig. —3—, whereupon the pivotal pin —15— may be passed edgewise through the slot into the bearing —12—.

As soon as the pin —15— is properly seated in the bearing —12—, the socket —13— may be rocked outwardly toward the axis of the coupling block, thereby causing the wider portions of the pivotal pin to assume a position transversely to said slot for locking the socket and coupling members together against relative endwise displacement, and, at the same time, permitting the socket to swing through an arc of substantially 180 degrees about the axis of the pivotal pin —15— which extends in a plane at right angles to the axis of the pivotal pin —8—.

A flat spring —16— is secured at one end to one side of the coupling block —10— and is provided with a pin —17— extending through an opening —18— in said side so as to normally project a short distance into the adjacent side of the slot —11— just at the outside of the pivotal pin —15— when the latter is seated in the cylindrical bearing —12—, the inner end face of said pin being rounded or inclined in the direction of length of the slot —11— to permit the pivotal pin to ride there-against and to move the same outwardly against the action of the spring —16— while the pin —15— is being moved into and out of the slot, or during the withdrawal and replacement of the socket member —13— from and upon said block, it being understood that when the socket member —13— is adjusted for use upon the block —10—, the inner end of the pin —17— serves to hold the socket member against accidental displacement when swung to an angle of 90 degrees from the axis of the coupling block while the walls of the circular

bearing —12— positively hold the socket member from withdrawal when in any other position than 90 degrees from said axis.

It will be noted that the diameter of the socket member —13— and width of the block —10— are less than that of the head —3— and that the shank of the handle is also of relatively less diameter than the head —3—, which permits the tool to be inserted in relatively small space for tightening and loosening nuts and bolts, and that the socket member —13— and coupling member —10— may be swung to different angles relatively to each other and to the axis of the head —3— to enable the socket to be used for tightening or loosening nuts and bolts which may be disposed at an angle to the handle of the tool, the universal joint formed by the pivotal connections between the socket member and coupling, and also between the coupling and head permitting the shank —1— of the tool to be turned about the same axis, while the socket may turn about another axis at an angle thereto.

What I claim is:

1. A tool of the character described comprising a shank having a handle at one end and a head rigidly mounted on the opposite end, said head being provided with axially extending lugs in spaced relation, a coupling member pivoted to and between said lugs to swing to different angles relatively to the axis of the head, said coupling being provided with a lengthwise slot opening from its outer end and having its inner end enlarged, a socket member having one end provided with axially extending ears in spaced relation, a pivotal pin rigidly secured to and between said ears and movable through said slot when turned to a certain position, the diameter of the pin at right angles to the axis of the socket being greater than the width of the slot to enter the enlarged inner end of said slot when turned to another position for locking the socket member and coupling member together against endwise displacement one from the other.

2. A tool of the character described comprising a shank having a handle at one end and a head rigidly mounted on the opposite end, said head being provided with axially extending lugs in spaced relation, a coupling member pivoted to and between said lugs to swing to different angles relatively to the axis of the head, said coupling being provided with a lengthwise slot opening from its outer end and having its inner end enlarged, a socket member having one end provided with axially extending ears in spaced relation, a pivotal pin rigidly secured to and between said ears and movable through said slot when turned to a certain position, the diameter of the pin at right angles to the axis of the socket being greater

- than the width of the slot to enter the enlarged inner end of said slot when turned to another position for locking the socket member and coupling member together
- 5 against endwise displacement one from the other, and a locking pin movable through an opening in the coupling partially across the slot at the outer side of the pivotal pin when seated in the enlargement of the slot
- 10 to assist in holding the coupling member and socket against relative endwise displacement, particularly, when the socket member is turned to the first named position.
- 15 3. A tool of the character described comprising a shank having a handle at one end and a head secured to the opposite end, said head being provided with diametrical opposite axially extending lugs, a coupling member having one end pivoted to and between said lugs and its opposite end provided with a diametrical extending slot of less length than the distance between the outer end of the coupling member and axis of the pivot, the inner end of said slot being enlarged to form a circular bearing, a socket member having a pivotal pin of greater width in one direction than that of the slot and of slightly less width than said slot in another direction, the greater width of the pin being substantially equal to the diameter of the circular bearing, said pin being normally seated in said bearing and held therein when its wider portion extends transversely of the slot and removable through said slot when its narrower portion is registered therewith.
- 20
- 25
- 30
- tends transversely of the slot and removable through said slot when its narrower portion is registered therewith.
4. A tool of the character described, comprising a shank having a handle at one end and a head secured to the opposite end, said head being provided with diametrical opposite axially extending lugs, a coupling member having one end pivoted to and between said lugs and its opposite end provided with a diametrical extending slot of less length than the distance between the outer end of the coupling member and axis of the pivot, the inner end of said slot being enlarged to form a circular bearing, a socket member having a pivotal pin of greater width in one direction than that of the slot and of slightly less width than said slot in another direction, the greater width of the pin being substantially equal to the diameter of the circular bearing, said pin being normally seated in said bearing and held therein when its wider portion extends transversely of the slot and removable through said slot when its narrower portion is registered therewith.
